DESIGN FOR A PICTURE FRAME OR SIMILAR ARTICLE

Rudi W. Mandl, Lakeland, Fla.

Application October 23, 1944, Serial No. 115,919

Term of patent 14 years

(Cl. D29—20)

To all whom it may concern:

Be it known that Rudi W. Mandl, a citizen of Czechoslovakia, but having declared his intention of becoming a citizen of the United States, and resident of the city of Lakeland, State of Florida, has invented a new, original, and ornamental Design for Picture Frame or Similar Article, of which the following is a specification, reference being had to the accompanying drawing, forming part thereof, in which,

Fig. 1 is a top plan view of a picture frame or similar article embodying my new design; and
Fig. 2 is an edge view thereof.

I claim:

The ornamental design for a picture frame or similar article, substantially as shown.

RUDI W. MANDL.
